Primary Examiner — Keith J Wilson**CLAIM**

(57) The ornamental design for a watering can, as shown and described.

DESCRIPTION

FIG. 1 is a perspective view of a watering can design showing my new design.

FIG. 2 is a front view of the watering can.

FIG. 3 is a rear view of the watering can.

FIG. 4 is a left side view of the watering can.

FIG. 5 is a right side view of the watering can.

FIG. 6 is a top view of the watering can; and,

FIG. 7 is a bottom view of the watering can.

Any shading is not a feature of the design but is utilized to illustrate the surface contours of the watering can design in the drawings.
